Robert Skinner

United States Patent Office.

ROBERT SKINNER, OF SAN FRANCISCO, CALIFORNIA.

Letters Patent No. 77,925, dated May 12, 1868.

IMPROVED MACHINE FOR MAKING DRAIN-PIPE.

The Schedule referred to in these Letters Patent and making part of the same.

TO ALL WHOM IT MAY CONCERN:

Be it known that I, ROBERT SKINNER, of the city and county of San Francisco, State of California, have invented an Improved Machine for Making Drain and Water-Pipes; and I do hereby declare the following description and accompanying drawings are sufficient to enable any person skilled in the art or science to which it most nearly appertains to make and use my said invention or improvements without further invention or experiment.

The object of my invention is to provide an improved machine for making drain and water-pipes, and consists of a stationary cylinder, in which a core is placed. A follower, attached to a piston-head, moves up and down around the stationary core, passing through slots in a centre-block. A closely-fitting packing-ring is placed around the core, and slides up and down upon it by the action of the piston or follower.

Another ring is placed at the top of the cylinder, and the cement or material of which the pipe is made is held between the two rings around the core in the cylinder. A cross-head is placed over the top ring, which is regulated by hand-wheels or set-screws. The pressure upon the material between the two rings is derived from the engine driving up the piston.

A steam-jacket is made around the cylinder, for heating the material used.

To more fully illustrate and describe my invention, reference is had to the accompanying drawings, and letters marked thereon, of which—

Figure 1 is a side elevation of my apparatus.

Figure 2 is a sectional elevation.

Figure 3 is a front view.

Figure 4 is a horizontal or cross-section at the line $z z$, on fig. 2, showing the core E, and its attachments, $a a$, to the centre-block B, corresponding to the slots $G' G'$, in the follower G, one of which is shown in fig. 2, also, the curved openings F F, through the centre-block in which the follower slides.

A is a base-block, and B a centre-block. Through the corners of these blocks pass pillars or supporting-posts, C C C C. The lower end and centres of these posts are turned so as to form shoulders, D D D D, affording space for the blocks to play up and down along the posts, and thereby preventing breakage if too great a power is applied to the machine.

To the centre-block is attached a core, E, which extends to near the upper ends of the posts. Through the centre-block are made curved openings, F F, in which a follower, G, moves up and down along the core, slots, $G' G'$, being made in it to avoid the attachment of the core to the centre-block, yet the centre-block and core may be cast in one piece, having the openings for the follower. The core is made slightly tapering, so that the pipe can be easily withdrawn from it after being compressed or formed around it.

By this construction of the follower and openings, the materials of which the pipes are composed are prevented from falling through the openings in the centre-block. The follower is connected to a piston or engine, H, which moves in the lower or base-block between the posts or pillars.

A cylinder, I, is placed on the upper face of the centre-block, where it is held by bolts passing through a flange and entering the block. The upper end of the cylinder is of a bell-shape, and the whole is provided with a steam-jacket, J, into which steam is introduced for heating the material employed, as in case where bitumen or pitch is used, and may be of advantage in winter, when pipes are to be made of cement.

At the top of the machine is placed a cross-head, K, which is attached by set-nuts or hand-wheels to movable bars or arms, L L, which are pivoted in slots made in the side-pieces or blocks M M, which are fixed to the upper ends of the four posts, and also kept in place by set-screws. When not employed, the cross-head can be moved from side to side of the machine, so that the pipe can be withdrawn, or weights and rings be introduced.

A closely-fitting ring, N, is placed around the core, and is moved up and down by the end of the follower. The follower being withdrawn, the material of which the pipes are composed is introduced to the cylinder at the top, and falls down around the core upon the ring, filling the entire space, when a ring, O, is placed in the

mouth of the cylinder, and a weight, P, placed on the ring, and the cross-head is brought over the mouth of the cylinder, the ring O being cut away on one side in order to allow the head-block to slide over it with ease, when it is screwed down by the hand-wheel or nuts. The power is applied to the piston-end of the machine, either by steam, hydraulic, hydrostatic, or other power, that will produce the required pressure. When this is attained, the cross-head and rings are removed from the top of the cylinder, and the same power used to force out the compressed pipe.

The ring O may be cut in different shapes to form a variety of openings at the end of the pipe; and for constructing a bell-shape for the top it may be removed entirely, and the weight placed at the top of the cylinder. For forming openings in the pipe, for connecting at right angles, a curved piece of metal, of the necessary size and shape, may be introduced between the core and cylinder.

Having thus described my invention, what I claim, and desire to secure by Letters Patent, is—

1. The follower G, constructed with slots G' G' and the curved openings F F, in which it slides, in combination with the stationary core E and ring N, substantially as and for the purpose set forth.
2. In combination with the above-claimed apparatus, I claim the steam-jacket J, for heating the same, and the material worked thereby, substantially as described.

In witness whereof, I have hereunto set my hand and seal.

ROBERT SKINNER. [L.S.]
